UNITED STATES PATENT OFFICE.

ROYAL E. HOYT, OF LOS ANGELES, CALIFORNIA, ASSIGNOR TO SCOTT E. ALLEN, HAL D. RIVES, AND FRANK CARROLL, ALL OF LOS ANGELES, CALIFORNIA.

SWING-SPOUT OIL-CAN.

1,330,538.

Specification of Letters Patent. Patented Feb. 10, 1920.

Application filed June 10, 1919. Serial No. 303,496.

To all whom it may concern:

Be it known that I, ROYAL E. HOYT, a citizen of the United States, residing at Los Angeles, in the county of Los Angeles and State of California, have invented a new and useful Improvement in Swing-Spout Oil-Cans, of which the following is a specification.

My invention relates to measuring vessels, and more particularly to oil cans which are used in selling lubricating oil to automobile drivers. In this particular application it is ordinarily necessary to pour the oil into the breather tube of the engine, which is often placed in more or less inaccessible places, so that the ordinary type of oil can is very difficult to pour.

In my invention I provide a spout which is normally carried in an upright position and which is dropped when it is desired to pour the oil, the measure being maintained in an upright position. It is, of course, necessary to provide a valve which opens only when the spout reaches its lower position.

The invention comprises the novel assembling of parts illustrated in the drawing in which—

Figure 1 is a side elevation of my invention.

Fig. 2 is a section on a plane represented by the line 2—2 of Fig. 1.

Fig. 3 is a section on a plane represented by the line 3—3 of Fig. 2; and

Fig. 4 is a section on a plane represented by the line 4—4 of Fig. 3.

In the embodiment of my invention shown in the drawings, the container 11 is provided with a handle 12 and with a false rim 13 secured to the bottom 14. A hole 15 is provided in the bottom 14, this hole communicating directly with an inlet opening 16 and a socket 17. This socket is tapered

to receive a valve 18 which has a valve opening 19 formed therein, this opening being 45 on the bottom with the parts in the position shown in Fig. 3.

The valve 18 is provided with a tight end 20 and a compression spring 21 is provided seating the valve 18 in the socket 17. A 50 spout 22 is secured to the end of the valve 18, extending upwardly as shown and having an inclined portion 23.

The method of operation of my invention is as follows:

The can being filled with oil, the spout 22 is thrown from the position shown in Fig. 1 in full lines to the position shown in dotted lines in that figure. With the parts in the position shown in Fig. 3, that is to say, 60 with the spout 22 at or near the vertical position, oil cannot flow through the hole 15 due to the fact that the opening 16 is closed by the valve 18. Whenever this valve is turned the valve opening 19 registers with the inlet opening 16 thus allowing oil to flow.

What I claim is:—

An oil can comprising walls forming a container having a hole in the bottom thereof, a tapered socket secured to the bottom of said container and having an inlet opening in open communication with said hole, a conical valve seating in said socket and projecting beyond the bottom of said container 70 and having a valve opening therein, spring means for holding said valve seated in said socket, and a spout secured at right angles to said valve in such a position that said valve opening registers with said inlet opening 75 when said spout is in the pouring position.

In testimony whereof, I have hereunto set my hand at Los Angeles, California, this 26th day of May, 1919.

ROYAL E. HOYT.
